DESIGN FOR A BRUSHING AND DRYING APPLIANCE

Willard L. Pollard, Evanston, Ill.

Application August 7, 1942, Serial No. 107,836

Term of patent 3½ years

To all whom it may concern:

Be it known that I, Willard L. Pollard, a citizen of the United States, residing at Evanston, in the county of Cook, and State of Illinois, have invented a new, original, and ornamental Design for a Brushing and Drying Appliance, of which the following is a specification, reference being had to the accompanying drawing forming a part thereof.

In the drawing,
Figure 1 is a perspective view showing a brushing and drying appliance; and

Fig. 2 is a section on the line 2—2 of Fig. 1.

I claim:

The ornamental design for a brushing and drying appliance, as shown.

WILLARD L. POLLARD.
